UNITED STATES PATENT OFFICE

153,492

DESIGN FOR A COMBINED KNIFE HOLDER AND SHARPENER

Arthur M. Berland, Chicago, Ill.

Application June 20, 1947, Serial No. 139,844

Term of patent 3½ years

(Cl. D44—29)

To all whom it may concern:

Be it known that I, Arthur M. Berland, a citizen of the United States, residing at Chicago, county of Cook, and State of Illinois, have invented a new, original, and ornamental Design for a Combined Knife Holder and Sharpener, of which the following is a specification, reference being had to the accompanying drawing, forming a part thereof, in which—

Fig. 1 is a top plan view of the combined knife holder and sharpener showing my new design;

Fig. 2 is a front elevational view thereof;

Fig. 3 is a side elevational view thereof.

I claim:

The ornamental design for a combined knife holder and sharpener, as shown.

ARTHUR M. BERLAND.
